CONTRIVANCES FOR A PATTERN MAKING LOOM

Emmerich Oeze Hoffmann, Santiago, Chile

Application September 19, 1955, Serial No. 535,173

7 Claims. (Cl. 139—33)

This invention broadly relates to the art of producing textile patterns, and to means for producing them, said means being adapted to facilitate a rapid, so to speak continuous production of a great variety of woven samples, what may be termed experimental textile samples or patterns of different designs without the heretofore required material and time-consuming and often difficult preparation or conditioning of weaving instrumentalities to effect the necessary changes in the orientation of yarn for the production of woven samples of changing designs, said means further facilitating the making of what may be termed immediate changes of patterns or sample weave designs in a continuous sequence.

In looms of present day construction there are employed one or more warp beams or similar means supporting substantial length of warp yarn. These substantial yarn lengths provide a so-to-speak continuous yarn supply. Such continuous yarn supply is entirely unsuitable for making substantially short sample runs or patterns of differing overall designs, but in which samples, threads of different colors, of different materials and of different qualities are to be employed, and wherein threads are to be specifically grouped to produce rapidly the most varied design effects.

In looms employing warp beams or similar means and the resulting continuous supply of warp yarn, the above outlined necessity of frequent yarn changes would present a most difficult, costly and very impractical manipulating problem. The present invention contemplates a most effective and simple solution of that problem.

That simple solution, which constitutes one of the prime objects of the present invention, is the method of speedily producing pattern samples and which method consists of the following essential steps: The employment of substantially short warp yarns, the removable fastening of one end of the yarns in a rear yarn carrier, passing the yarn through the shed-forming means and simultaneously through a mobile reed, fastening the other end of the warp yarns in front of said shed-forming means and tensioning the yarn, effecting successive weaving operations by forming yarn sheds by the use of several fingers and passing weft threads through the sheds.

The further, most important object of this invention is the provision of manually operable, simple means to facilitate making so-to-speak immediate changes of weaving designs in a continuously progressive and uninterrupted sequence.

The foregoing and numerous other important objects and advantages of the present invention will become more fully understood from the ensuing description, in conjunction with the accompanying drawings, wherein:

Fig. 1 is a more or less diagrammatical perspective view of a hand-operable loom in its presently preferred form and in accordance with the instant invention;

Fig. 2 is an elevation of one of the manually operable shaft structures employed in the loom; and

Fig. 3 is a fragmental perspective view of the front

2

part of the loom showing two adjacent shaft structures and the reed, as well as detent means for the shaft structures and means for effecting the disengagement of said shaft structures from said detent means.

5 In Fig. 1 there is illustrated a typical loom construction as used in connection with the present invention. There is shown a loom stand composed of a substantially long rear portion 10 and a shorter frontal portion 11, and between these portions there is disposed a plurality of spring-mounted shafts operative in shafts guide 12. Secured on top of rear stand portion 10 is a longitudinal carrier guide 13 supporting one or more rear yarn carriers 14, 14' and 14''. At the front portion 11 of the stand there is mounted a cloth roller 15 carrying a cloth tape 16. Roller 15 is provided with a handle or other means indicated at 17 for operating the same in rolling up tape 16. Between the roller 15 and shafts guide 12 are guide bars 18, operatively suspending a combination reed support and reed guide 19, upon which rests reed 20 shown in greater detail in Fig. 3. Reed 20 is intended to reciprocate between roller 15 and shafts guide 12, as will be presently explained.

Shafts guide 12 comprises two oppositely disposed ends or supports 21 and between these supports are guided and operatively mounted individual shafts 22, arranged in rows, one of which shaft is shown in detail in Fig. 2. From the horizontal ledges 21' of these supports depend springs 23 by means of which shafts 22 are operatively suspended. Each of these shafts is composed of a fixed outer frame 24, the vertical sides of which are provided with grooves 25. In these grooves there are supported and guided two resilient heddles-carrying, spaced, superimposed bars 26 which can be readily inserted into frame 24 or removed therefrom. Attached to the bars 26 are heddles 27 provided with heddle eyes 28. Heddles 27 can be bodily moved to either the left or right-hand end of bars 26.

In Fig. 1 there is shown between shaft supports 21 a plurality of shafts 22, and each of the shafts is provided with a hand grip 29, the hand grips of all shafts being numbered and are preferably arranged in staggered relation to one another. By means of hand grips 29 shafts 22 can be individually operated, that is can be moved in vertical directions relative to other shafts, as will be presently evident. Suspending springs 23 for all shafts are so designed as to hold the shafts at a substantially uniform, normal position, that is with the upper, horizontal members of frames 24 disposed in a level plane.

While suspension springs 23 are employed for the shaft frames, these shaft frames can be supported by compression springs if desired.

As illustrated in Fig. 1, only the first nine shafts are seen provided with hand grips for the sake of clarity. Obviously the shafts in rear of the first group of shafts, numbered 1 to 9, are meant to be also equipped with similar hand grips, numbered 10 to 18, 19 to 27, etc., except that the first group of hand grips will be the shortest and the next one longer and the last group longest to facilitate the depression of the shafts by the fingers of the hand.

60 In Fig. 1 shaft 22, having hand grip "1," is shown depressed and held in its depressed position. The means for holding any one of the shafts 22 in their depressed position are clearly illustrated in Figs. 2 and 3. The vertical members of frames 24 are shown to be provided with oppositely disposed recesses 30 and which recesses are adapted to be engaged by detents 31 when the shafts are first manually depressed and then released to be urged upwardly by suspension springs 23. Detents 31 are normally forced by springs 32 into engagement with frames 24. These springs are secured to portions of loom stand 10 as indicated in Fig. 2. Detents 31 are pivoted at 33

and are provided with ledges 34 upon which rest abutment springs 35 adapted to soften the impact of shafts 22 as they are being depressed by means of hand grips 29, and to elevate them to their normal position and to facilitate the release of the frames by the operation of the reed which slides on bearing bars 18.

Reed 20, shown clearly in Fig. 3, is provided with a frontal ledge 36 for the support and guidance of shuttles bearing weft threads, and which shuttles are illustrated at 37 in Fig. 1. The reed serves as batten. Depending from reed ledge 36 are vertical members 38 supporting at their lower ends detent-releasing bars 39. When any of the shafts are depressed and held in their depressed position by detents 31 and reed 20 is moved towards the shafts, detent-releasing bars 39 cause the disengagement of the detents from recesses 30 and permit spring 23 to elevate the shafts.

While in connection with Fig. 3 a specific arrangement of retaining and releasing means for the shafts is described, any other means for effecting similar results can be obviously substituted.

Referring again to Fig. 1, there will be seen next to cloth tape 16, a support 40 at the left thereof. Resting upon support 40 is front yarn carrier 41 by means of which the front ends of warp yarn can be temporarily held in place prior to their employment in the weaving operation, for instance, for pulling the threads through the heddle eyes or for tying or twisting the threads and for attaching them to an already used warp thread or to a group of warp threads. Front end yarn carrier 41 is portable and is adapted to be bodily moved along the left hand portion of the stand and can be temporarily rested upon any convenient point either of the left-hand stand portion 10' or the left-hand frontal support 40, the latter position of carrier 41 being illustrated in Fig. 1.

As the weaving operation progresses, more and more warp yarn is demanded, and to satisfy that yarn demand, front yarn end carrier 41 is successively moved from place to place along the left-hand side of the loom stand in rearward direction. Thus front end yarn carrier 41 functions as a temporary holder or retainer for one yarn end, which is here called the "front yarn end" while the other yarn end is either being conditioned or already is in condition for passage toward or through the loom mechanism.

At the right side of cloth tape 16 there will be seen a shuttle support 42 similar to carrier support 40, which latter can also be used as shuttle support if desired.

Referring again to Figs. 2 and 3, the detent arrangement for shafts 22 is shown in a specific form in these figures to indicate how the shafts, when depressed, are held in their depressed position. Obviously the detent arrangement illustrated is only indicative of the means for retaining shafts 22 in their depressed position, and any other effective shaft retention and shaft releasing means can be readily substituted.

From the above description of the present loom structure in connection with Figs. 1, 2 and 3, it becomes clearly evident that it differs materially from heretofore used hand looms.

The method

In order to facilitate the rapid production of sample patterns there are employed warp yarn threads of a limited length, that is of a length much shorter than that usually employed with looms provided with warp beams. Instead of warp beams delivering a "continuous" yarn supply there are provided rear end warp yarn carriers shown at 14, 14' and 14'', which are in the shape of bars supported upon a longitudinal carrier guide 13 and are movable and adjustable relative thereto. Upon these bars are mounted closely adjacent friction elements 43 which are adapted to hold either individual warp threads or a group of warp threads between them. Friction elements 43 preferably comprise closely adjacent rubber covered members so arranged that when a thread is placed be-

tween them such thread is held removably but sufficiently firmly, so that when the warp yarn is pulled, it is still retained in the carrier. In rear of elements 43 are preferably provided apertures for the reception of removable pegs 44, to which groups of threads can be tied, or twisted, such as warp yarn indicated at 45. By the use of substantially short yarn lengths it becomes an easy matter to change, group, rearrange or remove warp yarns in the loom, as compared with the difficult changes and replacement of substantially long, continuous yarn supplies carried by warp beams. Due to the employment of short warp yarn lengths it is relatively easy to pass individual warp yarn or groups of warp yarn through the heddle eyes of the different shafts. In order to facilitate the passage of yarn through the heddle eyes a shaft is depressed as shown for example in Fig. 1, wherein shaft "1" is lowered sufficiently by one hand to allow for the other hand to reach and pull forwards the desired heddles to effect passage of desired yarn through the heddle eyes. In other words the shafts can be lowered to positions at which sufficient space is provided for the above-stated hand operations. Such insertion of yarn is preferably effected by suitable hooks which not only bring the yarn through the heddle eyes but also, and simultaneously, through the blades of reed 20. Such hooks are not shown since their structure is rather obvious. When the passage of desired yarn through the heddle eyes and the reed is effected, the front ends of the yarn are attached to the end of cloth tape 16, and as the weaving operation progresses the cloth tape is wound by means of handle 17 upon roller 15. This cloth tape keeps the yarn under tension for the purpose of weaving.

The weaving procedure consists of the manual formation of yarn sheds and the passage through the sheds of weft threads carried by shuttles 37. The latter are alternately moved from the right toward the left and from the left toward the right. The formation of yarn sheds is effected by the depression by hand of desired shafts 22 and their retention in their depressed position until released by the operation of reed 20, thus permitting the latter to reassume their normal, elevated position adjacent to all stationarily retained shafts.

While in Fig. 1 only nine shafts are seen provided with manual grips 29, the shafts in rear of the last shaft No. "9" are intended to be also provided with similar hand grips. Any number of shafts 22 may be employed in guides 12.

A typical example of the weaving operation is as follows: Assuming that yarn sheds are to be formed, some of the shafts 22, say shafts 1, 3, 5, 7 and 9 are depressed to their lowermost position at which they are held by detents 31. Thus the threads carried by these depressed shafts are lowered, while the other shafts 2, 4, 6 and 8 remain at their normal, elevated position and their threads form the upper shed, whereas the threads in the depressed shafts form the lower shed. Now a shuttle 37 is passed through the sheds, being guided on ledge 36 of reed 20. The reed is then moved first towards the frontal ends of the warp yarn attached to cloth tape 16, the front edge of reed ledge 36 serving as batten. Thereupon the reed is moved rearwards, that is towards the shafts. The movement of the reed causes the release of the depressed shafts from detents 31 and the shafts reassume their normal, upward position. Now the even numbers of shafts are depressed to form a lower shed, while the odd numbers 65 retain their warp yarn in the upper position and form the upper shed. A shuttle with the weft thread is passed through the sheds and the reed is again moved first forward and then rearward towards the shafts, thus releasing the depressed shafts to reassume their normal position.

As now the weaving operations proceed, the finished woven samples are drawn forward by cloth tape 16, that is in the direction away from the shed-forming portion of the device, that is in the direction away from shafts frame 12. Obviously the warp yarn and rear ends carrier 14 are advanced forwardly.

When samples of the most varied patterns are desired it is relatively easy to quickly effect the necessary yarn changes, yarn arrangements and yarn grouping, by simply cutting the yarn which is no longer wanted and replacing same by other desired warp yarn, by removing the unwanted threads from the carrier, such as by cutting, and tying up or twisting-on the wanted new threads, the latter then being attached to the carrier in place of the unwanted threads. Due to the substantially short length of the warp yarn threads such changes, substitutions and various grouping of yarn can be readily effected.

Referring again to Fig. 1, it will be noted that the front group of shafts has hand gripping means numbered "1" to "9" of substantially the same height. When other shaft groups, in rear of the front group, are employed, their gripping means are made successively longer to facilitate the individual operation of the shafts in any group.

Referring again to Fig. 2 and particularly to the heddle-carrying bars 26, the latter are made preferably of resilient material so that they can be sprung out from and sprung into outer frame 24. Thus bars 26 are rendered readily accessible, and frame 24 can be placed on a table for arranging and positioning therein of bars 26 and of any number of heddles in these bars, whereupon frame or shaft 24 is replaced.

While in the foregoing a specific structure of a hand loom is described, it is obvious that simple variations in the construction of the different elements employed in the loom may become necessary as the production of the device progresses, such obvious changes being deemed to reside within the scope of the present invention as defined in the annexed claims.

What is claimed as new is:

1. In a pattern making loom, a loom stand having rear and front portions and a shafts mounting, a plurality of individual, manually operative heddle-carrying shafts movable in said shafts mounting, a mobile rear ends warp yarn carrier associated with the rear loom stand portion, a yarn front ends fastening and yarn tensioning roller at the front loom stand portion, a reed structure movable between said shafts mounting and said roller, individual warp yarn threads and assorted combinations of warp yarn groups, all of predetermined, limited length, extending between said yarn carrier and said roller and passing through eyes of the heddles in the shafts and through said reed, the rear portions of said yarn threads and of said warp yarn groups being frictionally but detachably held by said rear ends warp yarn carrier.

2. In a pattern making loom according to claim 1, and wherein each of the shafts is provided with means for manually positioning it within said shaft mounting in respect to other shafts, said positioning means of different shaft rows differing in length.

3. In a pattern making loom according to claim 2, and wherein tensional suspensions for said heddle-carrying shafts are provided in said shafts mounting so that all of the shafts are normally held at a uniform, elevated posi-

tion in said shaft mounting, and wherein the shafts are arranged in groups, and wherein said manual positioning means of said shafts is of a sufficient length to depress a shaft in respect to all other elevated shafts so as to facilitate and unencumbered operation of passing warp yarn through the eyes of heddles of the depressed shaft, and wherein said positioning means of the different shaft groups progress in length from the frontmost shaft group toward the rearmost shaft group, and wherein said positioning means of each shaft group are arranged in staggered relation to one another in the direction from the front to the rear.

4. In a pattern making loom according to claim 3, and wherein releasable detent means for said shafts are provided for retaining depressed shafts at their depressed position to cause the formation of a lower yarn shed, while the warp yarn held in the shafts which are maintained at their normal, elevated position forms the upper yarn shed.

5. In a pattern making loom according to claim 4, and wherein said reed structure is provided with a shuttle-supporting ledge for guiding weft thread holding shuttles through the formed warp yarn sheds.

6. In a pattern making loom according to claim 5, and wherein said reed structure is provided with means for causing said shaft detent means to assume a shaft-releasing position when said reed structure is moved after each passage of weft threads through the warp yarn sheds.

7. The method of rapidly weaving sample patterns on a warp-beamless loom having shed-forming means, the latter comprising a series of individual manually and independently operable, normally aligned shafts carrying heddles, said loom further having a mobile reed serving as a shuttle guide and as batten, said method consisting of removably fastening one end of a plurality of warp yarns to a linearly movable support in rear of said shed-forming means, passing the other end of the warp yarns through the heddles of the shafts and through the reed, tensioning the warp yarn by fastening its passed-through ends to a rotary tensioning element; forming warp sheds by manually altering the relative position of some shafts to some other shafts, passing a weft thread through the thus formed sheds, battening the weft thread by moving the reed away from the shafts, causing the warp yarns to assume parallel positions to one another by restoring the shafts to their normally aligned position, moving the thus formed weave course away from said shed-forming means by operating said tension element, and repeating the method steps of forming sheds, passing weft yarn through the sheds and moving the formed weave courses away from the shed-forming means.
